Atty.

UNITED STATES PATENT OFFICE

WILLIAM J. WALKER, OF WATERBURY, CONNECTICUT, ASSIGNOR TO UNITED-CARR FASTENER CORPORATION, OF CAMBRIDGE, MASSACHUSETTS, A CORPORATION OF MASSACHUSETTS

BAG FRAME AND FASTENER FOR THE SAME

Application filed September 16, 1931. Serial No. 563,064.

My invention aims to provide improvements in bag frames and fasteners for the same.

In the drawing which illustrates preferred embodiments of my invention:—

Figure 1 is an elevation view of an improved form of bag frame structure and fastening means for the same;

Fig. 2 is an enlarged section taken on the line 2—2 of Fig. 1, showing the fastener and bag frame members in closed positions; and

Fig. 3 is a section similar to that shown in Fig. 2, but showing the manner of unlocking the fastening means.

My invention is particularly, though not exclusively, adapted for use in connection with improvements in separable fastenings for hand-bags.

Referring first to the particular embodiment of my invention illustrated in the drawing, I have shown a pair of U-shaped frame members 1 and 2 (Figs. 2 and 3) of usual construction and hinged together for movement of one relative to the other. The frame members 1 and 2 which I have selected for illustration and description are U-shaped in cross-section with the open ends of the U facing outwardly (Figs. 1 and 2). It should be understood, however, that my improved separable fastening means for holding the two frame members in locked positions may be used with frame members of other cross-sectional forms.

The particular separable fastening means which I have illustrated comprises a member A which has a rounded portion 4 at one end and an L-shaped portion 5 at the other end. This member is secured to the U-shaped frame member 2 (Fig. 1) between the walls thereof by prongs 6 extending through the bottom of the U-shaped portion of the frame and bent against the under side. The upwardly extending portion of the L-shaped portion 5 lies adjacent to the inner wall of the U. If desirable, the upwardly projecting portion may be free to move relative to the wall of the U for purposes hereinafter described.

The second fastening member comprises a hinged member B preferably secured to the

frame member 1 in the same manner as the cooperating member just previously described. The hinged member B has a supporting portion 9 which is L-shaped and secured to the U-shaped frame member 1. The member B has spaced ears 10—10 (Fig. 1) at one end of the member 9 and between them is located an ear 11 of a pivotally movable block 12. The parts 8 and 9 are held in position by a suitable pin 12^a which passes through all three of the ears 10, 11 and 10, as shown in dotted lines in Figure 1.

The pivoted member 8 is in the form of an ornamental block of any suitable construction having a groove 14 cut in the bottom to receive the rounded portion 4 of the other fastener member, as shown in Fig. 2. The groove is cut at an angle and is curved in shape to provide a ledge 15 which cooperates with the rounded portion to hold the fastener members, against accidental separation.

If we assume that the fastener members are engaged, as shown in Fig. 2, separation is effected by pressing upon that side of the block 13 which overhangs the portion 4 thereby to tip the block about its pivot and rock the ledge 15 out of engagement with the portion 4, as shown in Fig. 3. During this operation the portion 4 must move toward the ears 10—10 and 11 of the pivoted fastener member to permit separation. This is effected (Fig. 3) by a movement of both of the above-named members toward each other by a twisting action of the frame members 1 and 2 relative to each other and may be effected partly by yielding of the upright portions of the L-shaped attaching portions depending somewhat upon the arrangement of the parts. After the fastener members have been released, the frames 1 and 2 assume their normal relationship.

To connect the fastener members the frame members 1 and 2 are moved together and then pressure is applied to the top of the block 13, thereby forcing the parts to yield by a camming action of the ledge 15 over the rounded surface of the portion 4. Thus I have provided for connection of the fastener members by a snap action.

While I have illustrated and described a

preferred embodiment of my invention I do not wish to be limited thereby, because the scope of my invention is best defined by the following claims.

5   Claims

1. A bag frame structure including a pair of frame members and separable fastening members for holding said frame members together, one of said frame members being U-shaped in cross-section with the open end of the U facing upwardly, one of said fastening members having an L-shaped attaching portion the bottom of which is rigidly secured to the bottom of the U-shaped frame member, a catch portion located at the upper end of said L-shaped attaching portion, a hinged portion provided by the other fastening member and carried by the other frame member, and said hinged portion having means for engagement with said catch when said catch is forced toward the frame member carrying the L-shaped attaching portion in a direction transverse to the frame members.
2. A bag frame structure including a pair of frame members and separable fastening members for holding said frame members together, each of said frame members being U-shaped in cross-section, each of said fastening members having an L-shaped attaching portion secured to one of the U-shaped frame members and interengaging means carried by said L-shaped attaching portions at their upper ends, said U-shaped frame members having their open ends facing upwardly and being yieldable away from each other adjacent to the closed ends during engagement and disengagement of the interengaging means of the fastening members.
3. A bag frame structure including a pair of frame members each of which is U-shaped in cross-section with the open end of the U facing upwardly, a fastening member having an L-shaped attaching portion secured within one of the U-shaped frame members, a fastener portion carried by said L-shaped attaching portion at its upper end and a second fastening member secured to the other frame member and having a cooperating fastener portion for interfastening engagement with the fastener portion carried by the first mentioned fastening member thereby to secure the frame members together.

In testimony whereof, I have signed my name to this specification.

33   WILLIAM J. WALKER.
